(54) **COFFINS, METALLIC**

(76) Inventor: **James A. Gray**

James A. Grant, Richmond, Virginia
Letters Patent

The Schedule referred to in these Letters Patent and making part of the same containing a description in the words of the said James A. Grant himself of his improvement is as follows, giving the metallic Coffins.

To all to whom these presents shall come, I, James A. Grant of Richmond in the County of Henrico and State of Virginia have invented a new and useful improvement in the manner of making coffins and covering them, and that the following is a full and exact description of the manner of constructing, and covering said improvements as invented by me — It consists in making the case or coffin of metal, and then entirely excluding any communication with the interior by means of the application of cement, to be additionally secured by the use of solder. In order to adapt the shape of the coffin to the application of the cement, I construct a groove all around the sides and ends on their upper and inner edges so as to form a counter sinking into which the lid is to drop upon the remains, when it causes to have been previously applied by soldering. My object is to prevent the escape of any disagreeable effusion from the body contained, within as well as for greater strength and security, and adapt the use of metal for the constructing of my coffins. Any kind will answer, but I should prefer zinc as possessing more strength and firmness than lead and yet being susceptible of being easily secured by a solder than either iron or brass &c. They may be formed either of sheet metal, or cast in the ordinary manner of hollow ware, and will be easily susceptible of such ornaments as desired in the process as may be desired. In the case of small sized ones I am a mounting around the outer edge of the lid when it will be necessary that the soldering should be done, around the side of it to prevent disfiguring the pallion, and would be sometimes

inconveniences in these words for full size. On the contrary it will be better that the lid should be counter-sunk simply & then can be soldered on the top. Should it be thought necessary in short and at a few notches, as braces may be need in the inside. or amongst the ornaments on the outside. The construction being thus explained. It remains to show the nature and application of the cement which I consist of the following ingredients viz. equal parts of Russian Resin and fine sharp sand or brick dust. If sand is used it should be properly dried & of its fine & dry particles. In order to apply it a narrow brush or other such instrument is all that is necessary, as it may in that manner be spread all along the construction & nothing more is necessary to do but to drop the lid into its place & the cement will adhere to both lid and coffin so securely as to effectively exclude water and air from entering. When zinc is used, the application of the soldering iron all around the joint will be an additional security, and in this manner is produced a perfectly tight and secure coffin, which may be kept in any situation without occasioning inconvenience to the living from the decomposition of the dead.

I that & claim as my invention and for which I now apply for Letters Patent is. the manner of constructing whalebone Coffins, as above described in doing them dry and take light by means of construction and soldering.

And testifying that the above is a full description of my invention as aforesaid by me at this time & day of my hand this twentieth day of April in the year Eighteen hundred & thirty one.
